Patented February 2, 1904.

UNITED STATES PATENT OFFICE.

JOHN MAXWELL, OF ONEIDA, NEW YORK.

DESIGN FOR A BURIAL-CASKET.

SPECIFICATION forming part of Design No. 36,769, dated February 2, 1904.

Application filed October 6, 1902. Serial No. 126,256. Term of patent 7 years.

To all whom it may concern:

Be it known that I, JOHN MAXWELL, a citizen of the United States, residing at Oneida, county of Madison, and State of New York, have invented a new, original, and ornamental Design for Burial-Caskets, of which the following is a specification, reference being had to the accompanying drawings, forming a part thereof, and in which—

10 Figure 1 shows a side view of the casket-

body. Fig. 2 shows an end view thereof, somewhat reduced in size.

I claim and desire to secure by Letters Patent—

The ornamental design for a burial-casket, 15 as shown.

JOHN MAXWELL.
